UNITED STATES PATENT OFFICE.

CHARLES F. ERICKSON, OF NEW YORK, N. Y.

HANGER.

Application filed June 6, 1924. Serial No. 718,382.

To all whom it may concern:

Be it known that I, CHARLES F. ERICKSON, a subject of the King of Sweden, residing at New York city, in the county of New York 5 and State of New York, have invented new and useful Improvements in Hangers, of which the following is a specification.

This invention relates to hangers and has for its primary object the provision of a 10 means for supporting a picture from the wall of a room without marring or defacing the wall as caused by the use of screws, nails or other like elements, and which may also be used as a garment hanger, or on a 15 fixture bracket for attachment to windows or the like.

Another object of the invention is to provide a hanger which is easily and quickly applied to the wall and when so applied, the 20 same is capable of supporting a relatively heavy weight.

A further object resides in the construction of a picture hanger which is simple in construction, cheap of manufacture and 25 highly ornamental and attractive in appearance.

With these and other objects in view, the invention resides in certain novel construction and combination and arrangement of 30 parts, the essential features of which are hereinafter fully described, are particularly pointed out in the appended claim, and are illustrated in the accompanying drawing, in which:—

Figure 1 is a perspective view of my invention complete.

Figure 2 is a plan view of the body member.

Figure 3 is a sectional view through the 40 attaching disk.

Figure 4 is a sectional view through the body member.

Figure 5 is a sectional view through a modified form of my invention.

Figure 6 is a plan view of the body member of the modification shown in Figure 5.

Figure 7 is a plan view of a further modified form.

Figure 8 is a sectional view on the line 50 8—8 of Figure 7.

Heretofore, it has been the practice of supporting pictures from the walls of a room by driving nails or the like into the walls which tends to mar and deface the wall paper, and when the nail is removed the same usually leaves a hole which is un-

sightly so as to distract from the neat appearance of the room. It has also been found convenient to support pictures from the molding strip, but this is also objectionable 60 as the hanging wire is exposed to view. It is therefore my intention to construct a hanger which will eliminate the above objections and which is easy to apply to the wall. 65

Referring more particularly to the drawing, the reference numeral 10 designates my improved hanger in its entirety and which is constructed of two parts, namely a supporting part 11 and an attaching part 12. 70 The part 11 is formed of a single piece of metallic material which includes a body 13 formed with an annular flange 14 which is bent or spun from the edge of the body. The body of the part 11 is cut out to form 75 an outwardly extending hook 15 for receiving the wire or other hanging member of the picture, the said hook being concavo-convex in cross section to strengthen the same. 80

The part 12 constitutes a felt disk 16 which is provided with an adhesive 17 on one side and an adhesive 18 on the opposite side thereof. The disk is applied to the back of the body 13 of the part 11 by moistening the adhesive side 17 and pressing the two parts together. Although I have mentioned the part 12 as being constructed of felt, it is to be understood that the same may be of paper or other similar material 90 if desired. The thickness of the disk is such as to slightly project beyond the edge of the flange to permit the same to yield when applying the hanger to the wall, but the flange serves to prevent undue spreading 95 of the disk during the yielding movement thereof.

When applying the hanger to a wall or like structure, the adhesive side 18 is moistened and placed against the wall in a position where it is desired to hang the picture. After being left to dry a few moments, the hanger is sufficiently strong as to permit the picture to be hung therefrom. If desired, the adhesive 18 can be covered by a paper 100 disk to preserve the adhesive until the hanger is to be used, and said paper disk may bear suitable instructions for applying the hanger to a wall. It will also be appreciated that the hangers may be made up 105 of different colors to match the furnishings or wall paper of a room. 110

In Figures 5 and 6 there is shown a slight modification wherein the body 13' is formed with an opening 19, arranged eccentric with relation to the center of the body. A removable picture hook 20 has one of its extremities inserted through the openings between the disk 16' and the back of the body. The remainder of this form is identical to the construction of the preferred form and a further description is therefore not deemed necessary.

In Figures 7 and 8 there has been shown a further modification wherein the metallic body member has been dispensed with. In this form, the numeral 21 designates a felt or paper disk similar to the disk 16 of the preferred form which has its rear surface covered with an adhesive 22. A supporting hook 23 is riveted to the front face of the disk as at 24 and serves the same purpose as the hooks 15 and 20. In this form the back of the disk is moistened and secured to the wall as hereinbefore mentioned.

I wish it to be understood that I do not limit myself to the shape of the hanger, al-

though the same has been shown as circular in plan it may be convenient and attractive to make the same of various shapes.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claim.

What is claimed as new is:—

A hanger comprising a body member having an annular flange, a yieldable disk seated within the annular flange and adhesively secured to the back of said body member, an adhesive surface formed on the exterior face of said disk, and a supporting hook stamped from said body member and extending from the front of the same.

In testimony whereof I have affixed my signature.

CHARLES F. ERICKSON.
